UNITED STATES PATENT OFFICE.

CARL A. WILL, OF SEATTLE, WASHINGTON, ASSIGNOR OF TWO-THIRDS TO OTTO WILL,
OF SEATTLE, WASHINGTON.

GRINDING AND POLISHING MACHINE.

1,006,419.

Specification of Letters Patent.

Patented Oct. 17, 1911.

Application filed December 8, 1910. Serial No. 596,285.

To all whom it may concern:

Be it known that I, CARL A. WILL, a citizen of the United States, residing at Seattle, in the county of King, State of Washington, have invented certain new and useful Improvements in Grinding and Polishing Machines; and I do hereby declare the following to be a full, clear, and exact description of the invention, such as will enable others skilled in the art to which it appertains to make and use the same.

This invention relates to grinding and polishing machines.

The object of the invention resides in the provision of a machine of the class described which includes improved means for reciprocating the work carrier longitudinally of the grinding wheel and in effecting the reciprocation of the work carrier by means of suitable connections between the same and the rotary shaft upon which the grinding wheel is mounted so that the rotation of the grinding wheel and the reciprocation of the work carrier will be accomplished through the instrumentality of a common means.

A further object of the invention resides in providing means whereby the connection between the work carrier and the rotary shaft carrying the grinding wheel may be disengaged and the grinding wheel operated independently of the work carrier.

A still further object of the invention resides in the provision of improved means for effecting the polishing and scouring of the work after the same has been acted upon by the grinding wheel.

With these and other objects in view, the invention consists in the details of construction and in the arrangement and combination of parts to be hereinafter more fully described and particularly pointed out in the appended claims.

In describing the invention in detail, reference will be had to the accompanying drawings, wherein like characters of reference denote corresponding parts in the several views; and in which,

Figure 1 is a plan view of a grinding and polishing machine constructed in accordance with the invention; Fig. 2, a front view of same; Fig. 3, a section on the line 3—3 of Fig. 1; Fig. 4, a section on the line 4—4 of Fig. 1; Fig. 5, an enlarged section on the line 5—5 of Fig. 2; Fig. 6, an enlarged

side view of the work carrier and the upper end of its support; and Fig. 7, a partial longitudinal section through the connection between the grinding wheel support and the work carrier support.

Referring to the drawings, the invention is shown as comprising a base 10, from which rises a standard 11. This base is also provided with a laterally extending portion 12 which has formed therein a groove 13 for a purpose that will presently appear. This groove has formed in its lower side openings 14 and 15, the purpose of which will presently appear. Journaled in the standard 11 is a shaft 16 which has fixed on one end thereof a grinding wheel 17 operated by a handle 18. This shaft 16 is also supported by a brace journal 19 projecting laterally of the standard 11. Also fixed on the shaft 16 is one section of a polishing wheel 20. Screwed into the end of the shaft 16 adjacent the wheel 20 is a section 21 which has fixed on its inner end a section 22 of the polishing wheel, the sections 21 and 22 being designed to form a complete polishing wheel and have their adjacent faces covered with leather or any suitable polishing material. The distance between the sections 21 and 22 is regulated by screwing the shaft section 21 into the shaft 16. Mounted on the extreme outer end of the shaft section 21 is a cloth scouring wheel 23 of the usual construction. Also fixed on the shaft 16 between the grinding wheel 17 and the standard 11 is a gear wheel 24 which meshes with a gear wheel 25 journaled on an extension 26 of the standard 11. Slidably mounted in the groove 13 is a base section 27 from which rises a standard 28. Journaled in this standard 28 is a shaft 29 which has fixed thereon a segmental gear 30. Secured to this segmental gear and arranged concentrically with respect to the shaft 29 is a crown gear 31 which meshes with the gear 25 so that the rotation of the shaft 16 will produce a rotation of the crown gear 31 and the segmental gear 30. Supported by the standard 28 and disposed longitudinally of the grinding wheel 17 is a frame A which includes parallel rods 32 and 33. Slidably mounted upon the rods 32 and 33 is a sliding block 34 which has detachably mounted in its upper end a work carrier support 35, while a mangle rack 36 is rigidly secured to the upper end of the block 34 and operatively en-

gages the segmental gear 30 so that the rotation of said gear will effect a reciprocation of the rack 36 and likewise the block 34 and the support 35. The upper end of the support 35 is forked to form the arms 37 and 37'.

The work carrier is shown as comprising a pair of plates 38 and 39 which are connected together by a screw member 40 where-
10 by said plates may be clamped together upon the work disposed therebetween. The plate 39 has extending from its lower face an ear 41 which is positioned between the arms 37 and 37' of the support 35, and piv-
15 otally connected to said support by means of a pivot pin 42 extending through said arms and said ear. Fixed on the pivot pin 42 adjacent one side of the support 35 is a toothed plate 43, upon one edge of which
20 the plate 39 is adapted to rest. A pawl 44 pivoted to the support 35 is adapted to engage the teeth of the plate 43 and hold said plate in a desired position so as to effect the proper adjustment of the work
25 carrier. After the adjustment of the plate 43, the work carrier is yieldingly held in engagement with one edge thereof by means of a spring 45, one end of which is secured to the lower face of the plate 39 and the
30 other end to the support 35.

By the construction so far described it will be apparent that upon the rotation of the shaft 16, the rack 36 will be reciprocated longitudinally of the grinding wheel 17 and
35 during this reciprocation, the work carrier will also be reciprocated longitudinally of the grinding wheel 17 and traverse the periphery of the latter and effect the proper grinding of the work carried thereby. When
40 it is desired to operate the grinding wheel 17 independently of the work carrier, the base member 27 is moved in the groove 13 so as to shift the crown gear 31 out of engagement with the gear 25, said base member
45 carrying a screw 47 which is adapted to be manipulated into the opening 15 when the gear 25 is in engagement with the gear 31, and into the opening 14 when said gears 25

and 31 have been moved out of engagement with each other.

50

What is claimed is:—

1. In a device of the class described, the combination of a frame, a shaft journaled on the frame, a grinding wheel fixed on said shaft, means for rotating said shaft, a 55 mangle rack mechanism mounted on said frame having its reciprocating member movable longitudinally of the grinding wheel, connections between the shaft and said mangle rack mechanism whereby the rotation of the former will actuate the latter, and a work carrier mounted on the reciprocating member of the mangle rack mechanism.

2. In a device of the class described, the combination of a frame, a shaft journaled on the frame, a grinding wheel fixed on the shaft, means for rotating said shaft, a work carrier support mounted on the frame for reciprocation longitudinally of the grinding 65 wheel, connections between the work carrier support and the shaft for effecting the reciprocation of the former by the rotation of the latter, said support having a forked upper end, a work carrier comprising a pair 70 of plates, connections between said plates for clamping same together, an ear extending from one of said plates and disposed between the arms of the forked end of the support, a pivot pin extending through said 75 arms and said ear whereby the work carrier is pivotally connected to the support, a toothed plate mounted on said pivot pin and adapted to support the work carrier, a pawl mounted on said support for engaging said toothed plate to hold same against movement under the influence of the weight of said work carrier, and spring actuated means constantly tending to force said carrier into engagement with said plate.

80

In testimony whereof, I affix my signature, in presence of two witnesses.

CARL A. WILL.
